UNITED STATES PATENT OFFICE.

HANNAH JACOBS AND HARRY JACOBS, OF BROOKLYN, NEW YORK.

HAIR DRYING AND STRAIGHTENING COMB.

1,217,454.

Specification of Letters Patent. Patented Feb. 27, 1917.

Application filed March 23, 1916. Serial No. 86,198.

To all whom it may concern:

Be it known that we, HANNAH JACOBS and HARRY JACOBS, citizens of the United States, and residents of Brooklyn borough, New 5 York city, in the county of Kings and State of New York, have invented certain new and useful Improvements in Hair Drying and Straightening Combs, of which the following is a specification.

10 This invention relates to improvements in hair drying and straightening combs and relates to that class of metal toothed combs wherein a means for heating the teeth is provided.

15 Numerous devices of this character are now on the market but none of them embody the improved features embraced in our invention.

20 The various hair drying combs now in use, while they accomplish the work they are intended to do they are so constructed, that they cool too quickly. No provision is made in any of these devices to maintain a high degree of temperature for a prolonged 25 period. And what we consider a further defect is the fact that the best devices, which employ a separate heating element, are not readily disassembled. A function which is greatly desired.

30 Our invention overcomes this last named defect and also provides a device wherein provision is made for maintaining a high temperature for a maximum period. We also provide a device which is simple in construction and economical in cost of construction.

35 We attain these objects by means of the apparatus illustrated in the accompanying drawing in which Figure 1 is a longitudinal 40 sectional view of the complete device; Fig. 2 is a sectional view taken on line 2—2 of Fig. 1; Fig. 3 is a sectional view of the comb proper or head with its attached insulating jacket; Fig. 4 is an end view of 45 same looking in the direction indicated by the arrow X; Fig. 5 is a view of the handle of the device and Fig. 6 is a view of the heating element.

Similar letters refer to similar parts 50 throughout.

Our device consists of the hollow metal comb head 1 having comb teeth 2. The said hollow head is closed at one end 3 and pro-

vided with an internal threaded portion 4 at the other end in which a correspondingly threaded portion 5 of the handle 6 engages. The threaded portion 5 is formed upon a metal shank 7 which is secured to the handle 6 by any suitable means preferably as indicated in Fig. 1. 60

A recess 8 is formed upon the shank 7 and is adapted to receive a pin 9 formed upon a heating element 10. This heating element is made of any metal or material which will absorb a great amount of heat and is adapted to be placed within the hollow head 1. 65

The said hollow head 1 is inclosed within an insulating jacket 11 which is slotted along its lower side as at 12 to allow the same to be forced over the head 1 and pass the teeth 2. 70 The said insulating jacket 11 is made of an asbestos fiber or "red fiber" commonly called "fiber" in the electrical trades.

The entire apparatus consists essentially of three members; namely, the head as embraced in Fig. 3, the handle shown in Fig. 5, and the heating element indicated in Fig. 6. These parts are all readily disassembled and may be made up into a very compact bundle for convenience in carrying. The illustrations are approximately full size. 80

In use the heating element 10 is heated to the desired temperature by any approved means and is then lifted by means of the handle 6, which is made of wood or any material which is a poor conductor of heat. The pin 9 of the member 10 fits loosely in the recess 8 in the handle 6 and is therefore easily taken up. The head 1 is then passed over the said heating element and the threaded 90 portions on the head and handle screwed tightly together. In a short time the heat of the heating element will be transmitted to the comb teeth and the comb is ready for use. 95

In Figs. 2 and 4 we have shown curved comb teeth but the regular straight teeth may be employed.

It is obvious that we may embody various modifications without departing from the spirit of our invention. We do not, therefore, wish to limit ourselves to the particular construction shown but what we claim and desire to secure by Letters Patent is 100

In a hair drying and straightening comb, a hollow metallic head having comb-teeth 105 formed thereon, a handle formed of heat in-

sulating material and adapted to be detachably connected to the said head, a heating element adapted to engage within the said head, a lifting pin formed upon one end of said heating element and a recess formed in aforesaid handle and adapted to engage the said pin to lift same.

Signed at Brooklyn in the county of Kings

and State of New York this 20th day of March A. D. 1916.

HANNAH JACOBS.
HARRY JACOBS.
